UNITED STATES PATENT OFFICE

JAN POREL, OF NEW YORK, N. Y., ASSIGNOR TO MAXIMILIAN WEIL, OF NEW YORK, N. Y.

DESIGN FOR A CLOCK CASE

Application filed February 20, 1931. Serial No. 38,752. Term of patent 14 years.

To all whom it may concern:

Be it known that I, JAN POREL, a citizen of the United States, and residing at New York city, in the county of New York and State of New York, have invented a new, original, and ornamental Design for a Clock Case, of which the following is a specification, reference being had to the accompanying drawing, forming part hereof.

The figure is a perspective view of a clock case showing my new design.

I claim:

The ornamental design for a clock case as shown.

JAN POREL.
